CABINET FOR A VEHICLE CLEANING MECHANISM

Jeffrey Martyn Sass, London, England, assignor to Vacmobile Manufacturing Company Limited, London, England, a British company

Filed July 15, 1963, Ser. No. 75,786

Claims priority, application Great Britain Feb. 7, 1963

Term of patent 14 years

(Cl. D49—1)

Fig. 1.

Fig. 2.

Fig.3.

FIGURE 1 is a perspective view showing the front and one side of a cabinet for a vehicle cleaning mechanism,

FIGURE 2 is a perspective view from above showing the top, the front and the other side of the cabinet, and

FIGURE 3 is a perspective view showing the back and one side of the cabinet.

The dominant features of my design reside in the portions shown in full lines.

I claim:

The ornamental design for a cabinet for a vehicle cleaning mechanism, substantially as shown and described.
